UNITED STATES PATENT OFFICE.

FRANCIS J. PEIRCE, OF BOSTON, MASSACHUSETTS, ASSIGNOR TO ROXBURY CARPET COMPANY, OF SAME PLACE.

DESIGN FOR A CARPET-PATTERN.

Specification forming part of Design No. 5,897, dated June 4, 1872.

SPECIFICATION.

I, FRANCIS J. PEIRCE, of Boston, State of Massachusetts, have invented and produced a new and original Design for Tapestry Carpets, of which the following is a specification:

The nature of my design is fully represented in the accompanying photographic illustration, to which reference is made.

Claim.

I claim as my invention—
The design for a tapestry carpet, as shown.
FRANCIS J. PEIRCE.
